UNITED STATES PATENT OFFICE

99,367

DESIGN FOR A SHOE

Gustav Peterson, New York, N. Y.

Application March 14, 1936, Serial No. 61,626

Term of patent 3½ years

To all whom it may concern:

Be it known that I, Gustav Peterson, a citizen of the United States of America, residing in Manhattan, county of New York and State of New York, have invented a new, original, and ornamental Design for a Shoe, of which the following is a specification, reference being had to the accompanying drawing, forming part thereof, wherein,

The characteristic feature of my design resides in the double brogue foxing.

I claim:

The ornamental design for a shoe, substantially as shown, and described.

GUSTAV PETERSON.
